UNITED STATES PATENT OFFICE.

CLARENCE D. PLATT, OF BRIDGEPORT, CONNECTICUT.

ELECTRIC-SWITCH CONSTRUCTION.

1,260,708.

Specification of Letters Patent. Patented Mar 26, 1918.

Application filed July 21, 1917. Serial No. 181,957.

To all whom it may concern:

Be it known that I, CLARENCE D. PLATT, a citizen of the United States of America, residing at Bridgeport, Connecticut, have 5 invented a new and useful Electric-Switch Construction, of which the following is a specification.

My invention relates to electric switches and particularly to a switch of the inclosed 10 type. This invention aims chiefly at improving certain features of construction set forth and claimed in my copending application #152,256, filed March 3rd, 1917.

The object of the present invention is to 15 provide simple and effective means for holding the operating handle in place, which means may also act as a stop to limit the throw of said handle. I also in the present case provide means for automatically locking 20 the switch in the open position while the switch box is open, thereby making it possible for any one to insert or remove fuses, for example, without danger of injury. This automatic locking means I also 25 preferably construct in such a way that while its normal effect is to lock the switch handle in the open position, it may, nevertheless, be released so that the switch may be tested while the box is open. It requires, 30 however, a special manual act to release said handle from the open position.

These and other advantages will be apparent to the mechanic skilled in the art, from a reading of the following description, 35 and an examination of the accompanying drawings, in which:

Figure 1 is a front view of the switch and the containing box, the box cover being open.

Fig. 2 is a side elevation partly broken 40 away, the box cover being closed.

Fig. 3 is a cross section on approximately the line 3-3 of Fig. 1.

Fig. 4 is a perspective view of a detail.

10 represents an insulating base which carries all the conducting parts of the switch except the movable switch member. 11-12 are stationary contacts suitably secured to the base and to which the incoming circuit wires are attached by any suitable means, 45 such as binding screws. 13-14 are stationary contacts carried by the base which respectively are designed to be connected by the switch blades 29-30 with contact plates 11-12. The contacts 13 and 14 are electrically connected with suitable sockets 17-18 designed to receive fuse plugs. The outgo-

ing terminal pieces from the fuse plug sockets are indicated respectively at 19-20, and the same may be provided with binding posts or screws, as shown, for the outgoing 60 circuit wires. 28 is an insulating cross bar which carries the switch contacts 29 and 30 which are preferably laminated and arch shaped, as in my previous application. 31-32 are springs which carry the cross bar 65 28 and which normally tend to move the bar in a direction to open the circuit from 11 to 13 and from 12 to 14.

The operating means for the switch comprises an operating handle 34 arranged at 70 the side of the box and connected to a shaft 35 which extends through the sides of the box and is provided with an offset crank or cam portion 36 which has a sliding movement upon a wear plate 40 carried by the 75 cross bar 28.

The shape of the crank 36 is such that the shaft may be easily passed through the bearing openings in the opposite sides of the box when the parts are assembled or disassembled. 80

25 is a box or receptacle for the switch and 26 is a cover therefor, hinged at one end of the box. 38 is an offset shoulder on the edge of the cover which is arranged to 85 engage the handle when the box cover is being opened so as to throw the handle in the switch opening direction, thus guaranteeing the opening of the circuit when the box is opened. 90

The parts thus far briefly described are substantially similar to the corresponding parts shown and described in my aforesaid copending application, and obviously further detail description is unnecessary. 95 Furthermore, it should be understood that I contemplate that the switch mechanism *per se* and the associated parts are capable of a wide range of modification, without departing from the spirit and scope of the 100 present invention.

In the present case I provide a means which operates as a combined stop and retainer for holding the handle and shaft in the operative position. This device comprises a strap 1 having laterally projecting offsets 2-2 at opposite ends, which are of such length as to afford suitable clearance between the side of the box and the strap 1 for the handle 34, see Fig. 1. This strap 110 may be connected to the side of the box in any suitable manner and when secured in

place serves alone to hold the shaft 35 in its operative position in the box irrespective of the position of the handle 34. The offsets 2-2 of the strap not only serve to give 5 to the strap the proper spacing, but are so positioned as to act as limiting stops to check the swinging movement of the handle in the "on" and "off" switch position.

3 is the nose of an automatic latch. This 10 nose projects outwardly through an opening in the side of the box, the inner end of said nose having a suitable spring support 4 tending normally to project the latch nose outwardly. The spring support 4 may be 15 secured to the inside of the box by any suitable means such as a rivet or screw 5. The nose 3 is provided at one edge with an abrupt face and is so positioned as to engage and hold the handle 34 in the "off" 20 position. The opposite edge of the nose is beveled so that the handle may swing from the "on" to the "off" position, incidentally depressing the nose by engagement with the beveled edge thereof. The upper side 25 of the latch nose is beveled or inclined in any suitable way so that when the cover is shut down, a flange at the edge of the cover will engage said incline and press back the latch nose as shown in Fig. 3, thus leaving 30 at such a time the handle free to be moved in either direction.

Operation: When the box cover 26 is opened it first frees the latch nose 3 so that it projects into the handle engaging and 35 holding position. The continued opening movement of the box cover automatically swings the handle from the "on" position toward the "off" position and until the handle can be moved by the pressure of the 40 springs 31-32 to the full "off" position. This movement of the handle normally depresses the latch nose 3 until the handle passes the latch nose whereupon the latter springs out again into the handle engaging 45 position, shown in Figs. 1 and 2, wherein it will be held so long as the box is open, although even at such a time an expert could release the handle for the purpose of closing the switch and testing the same, or the 50 circuit, by simply inserting a suitable tool, such as a screw-driver under the latch so as to force it back. When the cover is again closed it depresses the latch and leaves the handle free to be moved "on" or "off" 55 as before stated.

I claim:

1. In a switch construction, an insulating base, contacts carried thereby, a movable switch element for closing a circuit through 60 said contacts, a box having a cover for inclosing said parts, an operating means for said movable switch element comprising a shaft passing through openings in the opposite sides of the box and having an off set portion for co-operation with the mov- 65 able switch element, a handle at one end of said shaft arranged externally of the box and at one side thereof, said handle including a crank arm connected with the end of said shaft, means carried by the box 70 including a strap overstanding said crank arm in its several positions for holding said shaft against disengagement from said box, and means for latching the crank arm in the "off" position, said means projecting 75 into the space between the strap and the side of the box.
2. In a switch construction, an insulating base, contacts carried thereby, a movable switch element for closing a circuit through 80 said contacts, a box having a cover for inclosing said parts, an operating means for said movable switch element comprising a shaft passing through openings in the opposite sides of the box and having an offset 85 portion for co-operation with the movable switch element, a handle at one end of said shaft arranged externally of the box and at one side thereof, said handle including a crank arm connected with the end of said shaft, means carried by the box including a strap overstanding said crank arm in its several positions for holding said shaft against disengagement from said box, de- 90 pressible means for latching the crank arm 95 in the "off" position, said means projecting into the space between the strap and the side of the box, and disposed in the path of movement of said crank arm so as to be depressed thereby when the same is moved 100 from the "on" to the "off" position.
3. In a switch construction, an insulating base, contacts carried thereby, a movable switch element for closing a circuit through 105 said contacts, a box for inclosing said parts, said box having a movable cover, an operating means for said movable switch element comprising a shaft passing through openings in the opposite sides of the box and having an offset portion for co-operation 110 with the movable switch element, a handle at one end of said shaft arranged externally of the box and at one side thereof, said handle including a crank arm connected 115 with the end of said shaft, means carried by the box including a strap overstanding said crank arm in its several positions for holding said shaft against disengagement from said box, de- 120 pressible means for latching the crank arm in the "off" position, said means projecting into the space between the strap and the side of the box, and disposed in the path of movement of said crank arm so as to be depressed thereby when the same is moved 125 from the "on" to the "off" position.
4. In combination, a switch, a box inclosing said switch, a shaft for operating the switch journaled in the box independently 130

- of the switch and having an integral angularly bent end portion disposed outside the box and forming a handle by which the switch can be operated, and a strap overlying 5 the angularly bent handle portion of the shaft to form a housing for said handle limiting the outward shifting movement of the shaft, said strap having angularly bent end portions by which it is attached to the box, 10 and said angularly directed end portions of the strap forming stops for limiting the rocking movement of the handle in both directions, said shaft being bodily removable from said box without disassembling said 15 switch when said strap is removed.
5. In a switch construction, switch mechanism including a movable switch member, a box for said parts including a movable cover, an operating device for the movable 20 switch element including a handle located externally of said box, means for locking said handle in the position in which the switch is open when the box cover is open, said locking means being disposed in the path of movement of the cover and moved to the non-locking position by the closing of said cover, and a flange on the outside of the cover disposed in position to engage the externally located handle, and to shift such handle to the 25 "off" position in the opening movement of the cover, the locking means aforesaid being de-pressible by the handle in the movement of said handle to the "off" position on the opening of the cover.
- 30 6. In combination, a switch, a box inclosing said switch, a shaft for operating the switch journaled in the box and having an integral angularly bent end portion disposed outside the box and forming a handle by 35 which the switch can be operated, a strap overlying the angularly bent handle portion of the shaft to form a housing for said handle limiting the outward shifting movement of the shaft, said strap having angularly bent 40 end portions by which it is attached to the box, and said angularly bent end portions of the strap forming stops for limiting the rock- 45
- ing movement of the handle in both directions, and an automatic stop projecting into the housing provided by the strap to engage 50 the angularly bent handle at a point intermediate the stops at the ends of the strap, said handle being held to move in the stop operating plane by said strap.
7. In combination, a switch including a 55 movable switch element, a box inclosing said switch, an operating shaft journaled in the side of the box and having an operating connection with the movable switch element, said operating shaft having an integral angularly bent end portion outside of the box providing an operating handle, a strap secured to the side of the box having a portion spaced away from the side of the box and entirely overstanding the angularly bent end 60 portion of the shaft to thereby form a housing covering the bent end of the shaft and preventing disengagement of said shaft from the box wall in which it is journaled, a de-pressible stop for the handle projecting into 65 the housing thus provided for the handle end of the shaft and arranged to be de-pressed by the handle in the movement of said handle in one direction, said box having a movable cover and said cover engaging the 70 de-pressible stop in the closed position of the cover to hold said stop retracted out of the path of movement of the handle when the cover is closed.
8. In combination, a box having a movable 75 cover, a switch in the box including a movable switch element, a switch operating handle disposed externally of the box, a stop for locking the switch handle in the "off" position when the cover is open, a member 80 on the cover for retracting said stop when the cover is closed to thereby enable free operation of the handle when said cover is closed, means for automatically projecting the stop into holding position as the cover is opened and means on the cover for throwing the handle to the "off" position as the cover is opened.

CLARENCE D. PLATT.
